SEWING MACHINE

James H. Van Vorst, Dumont, N. J., assignor to
 Willcox & Gibbs Sewing Machine Company,
 New York, N. Y., a corporation of New York

Application April 1, 1944, Serial No. 529,083

15 Claims. (Cl. 112—221)

1

This invention relates to sewing machines, and more particularly to non-automatic means for restrainedly and deliberately moving the needle and needle bar of a machine to advanced or retracted positions after the machine has finished part of a stitching operation.

When stitching material by means of the usual sewing machine, it is common practice, often each time the machine is stopped upon completion of some stitching, to operate the needle and needle bar of the machine by grasping the hand wheel and turning same for the purpose of either lifting the needle out of the work, or embedding it deeply into the work, depending on whether the latter is to be moved bodily to a new position, or merely turned for changing the direction of sewing.

In some instances machines have been provided with automatic stop mechanisms whereby the needle is always lifted entirely out of the work when the machine is brought to a standstill, but this is not always desirable, especially if the machine has to be stopped for abruptly changing the direction of stitching.

The advantage of manual control of the needle, as compared with automatic control, is that an operator is enabled to readily meet the various requirements of shifting and turning of the work when carrying out diversified sewing operations. However, when employing this method, before the operator can use two hands to raise the presser foot and manipulate the work for the next stitching operation as is often necessary, he must first use one hand on the handwheel to position the needle either in or out of the work. This is wasteful of time, and often inconvenient, as well as tending to tire the operator.

It is an object of the present invention to provide an improved needle control mechanism which obviates the above disadvantages by enabling an operator, without the use of his hands, to quickly and conveniently adjust the needle position after the machine has been stopped. Thus both hands of the operator are immediately available for raising the presser foot and manipulating the work to a new position, without lost time and tiresome extra movement.

This is accomplished by providing a novel foot or leg-operated mechanism having a normally disengaged connection with a driving shaft of the machine whereby the normal running of same is not interfered with, yet, when the machine is at a standstill, the mechanism can be operated to restrainedly turn the shaft and position the needle as desired.

2

A feature of the invention is the provision of a needle adjusting mechanism as above described wherein, if the machine is inadvertently started during use of the mechanism, no damage will result to the operator, nor to any of the parts of the mechanism, and there will be no delay whatsoever in the sewing operations. Thus an operator's speed or production is not hampered by having the mechanism on a machine.

10 Another feature of the invention is the provision of a mechanism as above wherein the parts are few and simple to manufacture and install on existing machines, and wherein they may be quickly and conveniently replaced.

15 Other features and advantages will hereinafter appear.

In the accompanying drawings:

Figure 1 is a front elevation of a sewing machine showing the present invention applied thereto.

20 Fig. 2 is a section taken on the line 2—2 of Fig. 1.

Fig. 3 is a view similar to that of Fig. 2 except that it shows the auxiliary needle-operating mechanism in engaged or working position.

25 Fig. 4 is a fragmentary front elevation showing a modification of the present invention.

Fig. 5 is a fragmentary right side elevation of the modification of Fig. 4.

30 Fig. 6 is a face view of the cam for controlling the clutch of the modification of Fig. 4.

Fig. 7 is a face view of the follower disk for the cam of Fig. 6.

As shown in Figs. 1 and 2, the machine embodying the present invention comprises a bench top 10 carried on legs 11 and supporting a machine worktable 12 having a vertical post 13, horizontal arm 14 and sewing head 15. A needle 16 is carried by the head 15 for reciprocating movement in the usual manner, said needle being operated in response to turning of the main shaft 17 of the machine. The usual looper mechanism (not shown) is located within the table 12 below the needle 16, and operated in connection with turning of the shaft 17 to produce stitches in work fed past the needle 16. The shaft 17 carries a handwheel 18 and pulley 19, the latter being driven by a belt 20 from a suitable source of power, such as a motor 21.

35 The machine as operated for sewing may receive its motive power by means of the belt 20 and pulley 19, and when the machine is to be stopped after completing a group of stitches, the driving force is removed from the belt 20, as by 40 switching off the current to the motor 21. When

this is done, the needle 16 and operating mechanism therefor including the shaft 17 will come to a standstill in any one of a large number of possible positions. This position may be such that the needle is more or less extended into the work, or it may be entirely retracted. Prior to the present invention, in order to position the needle in either retracted or extended position as desired, the operator had to reach up, grasp the handwheel 18 and turn the necessary amount.

According to the present invention this time and attention consuming operation is obviated by providing means for controllably moving or positioning the needle 16 of the machine after the latter has come to a standstill which may be operated or controlled by some part of the operator's body or limbs other than his hands, for instance, by his knee or leg. Thus the operator has the free use of his hands to manipulate the presser bar and the work as may be required, and in addition to the saving in time, the elimination of the handwheel manipulation results in a simplification of the motions required of an operator, and therefore a reduction in fatigue.

In the form of this invention illustrated herein, as exemplary thereof, the needle positioning mechanism is adapted to be operated in response to movement of the operator's knee, thus leaving the operator's feet free to remain on any other controls such as the motor control which they usually operate.

The mechanism for accomplishing this, as shown in Figs. 1, 2 and 3 comprises a disk 22 rigidly fastened to the shaft 17 and having buttress teeth 23 around its periphery, the teeth being positioned so that during forward rotation of the shaft the sloping face of each tooth leads the driving faces thereof.

For the purpose of engaging and driving the disk 22, a vertically positioned rack 24 having a lateral extension 25 at its lower end is pivotally and slidably mounted in a vertical guide 26 fastened to the post 13. The rack or driving member 24 has buttress teeth 27 along one edge which are positioned and adapted to engage the teeth 23 of the disk to drive the latter, the driving face of each of the teeth 27 being on the underside thereof, and the sloping face on the upper side.

The extension 25 of the rack is apertured near its center to receive a pivot screw 28 about which the rack may swing, said screw being carried by a roller 29 which is movable in a vertical groove 30 of T-cross section, in the guide 26. The upper end of the groove 30 is provided with a closure 31 functioning as a stop for the roller 29, and a helical compression spring 32 is located in said groove to engage the roller 29 and yieldably hold same against the closure 31, the lower end of the spring 32 being anchored against a closure 33 at the lower end of the groove. The diameter of the coils of the spring 32 is sufficiently great to cause it to be confined in the groove and prevent its buckling and extending out of the narrow throat thereof.

As thus mounted, see Fig. 2, the rack 24 may be pivotally moved so that the teeth 27 thereof will engage the teeth 23 of the disk for driving the latter, and this driving may be accomplished by bodily moving the rack 24 downwardly, while its teeth are engaged, against the yielding pressure supplied by the spring 32. When this is done, the shaft 17 will be caused to rotate in a clockwise direction as indicated by the arrow in Fig. 3.

For the purpose of operating the rack 24, a link 34 is provided, extending through an aperture

35 in the bench 10, the upper end of the link being pivotally connected to the rack at the end of the extension 25 thereof, the latter being apertured and having a pivot screw 36 to provide this connection. The link 34 passes through a laterally extending apertured lug 37 at the lower end of the guide 26 and under the bench 10, the lower end of the link is pivotally connected to an operable member 38 which is in turn pivotally carried by 10 a bracket 39 fastened to a horizontal brace 40 across the legs 11. The member 38 has a depending extension 41 adapted to be engaged by the thigh or knee of an operator, so that pressure thereon will cause the member to pivot and turn 15 in a counterclockwise direction; (see Fig. 1) and cause the link 34 to be moved downwardly.

In order to provide for return movement of the operable member 38 and link 34, and also to yieldably hold the rack 24 out of engagement with the disk 22 a helical compression spring 42 is carried on the link so that its ends respectively engage and press against the lug 37 of the guide and a collar 43 adjustably mounted on the link adjacent the pivot 36. The pressure of the spring 42 may be adjusted to the desired value by shifting and locking the collar 43 on the link 34, a set screw being provided in the collar for this purpose. The link 34 also carries a collar 43b held by a set screw and located to engage the underside of the lug 37 of the slide to function as a stop when the rack 24 is in the disengaged position of Fig. 2.

Another means which functions to disengage the rack 24 from the disk 22 upon release of the operable member 38 is shown, in the form of a lateral extension 25a on the lower end of the rack 24, adapted to engage a pin 25b mounted on the post 13 when the rack is being returned by the springs 32 and 42 after being operated to position the needle. Engagement of the pin 25b and extension 25a serve to pivot the rack in a counterclockwise direction, looking at Fig. 2, as the spring 32 continues to expand, thus separating the rack from the disk 22.

The rack 29 and gear 22 of the improved needle positioning means as above set forth function in the manner of a clutch. During normal operation of the machine for sewing, the rack 24 is yieldably held in the disengaged position of Fig. 2 by the spring 42, and the machine runs entirely free from any influence of the positioning means. When the machine is brought to a standstill and it is desired to project or withdraw the needle 16, the operator merely presses with his leg against the extension 41 of the operable member, as shown by the arrow in Fig. 1. This moves the link 34 downwardly, causes the rack 24 first to pivot so as to engage the teeth 27 thereof with the teeth 23 of the disk 22 and then to bodily move downwardly against the pressure of the springs 32 and 42 so as to slowly and controllably drive the disk 22 in a clockwise direction, as in Fig. 3. This turns the shaft 17 forwardly, and by this method the needle 16 may be adjusted or positioned either up or down, the final position of the needle depending upon the point at which the needle stopped and the amount of movement imparted to the mechanism by the operation of the lever 41 necessary to continue the drive until the desired position is reached.

For instance, when the machine stopped the needle may have just left the work and the operator may desire to have the needle penetrate and impale the work. In this case, the lever 41 would be operated to cause the needle to continue to rise 75 and then descend until it entered and held the

work. With the device of this invention, because of the leverage between the lever 41 and the shaft 17, the latter may be moved smoothly and under complete control to bring the needle to desired position.

The movement of the lever 41 need not be accomplished with any special caution or care for if the desired position of the needle is overshot the lever 41 may be again operated to reach it. An experienced operator observing the position of the needle quickly learns the amount of movement to give the lever, and whether the movement should be accomplished by a light blow or tap or by follow-up pressure. When the operator removes the pressure against the extension 41, the action of the springs 32 and 42 will return all the parts to the position of Fig. 2, in readiness for sewing to be resumed.

By providing teeth on the disk 22 and rack 24 in buttress form, the clutch comprising these parts is adapted for one way drive only, and during the return of the rack to its disengaged position of Fig. 2, the teeth may slide or ratchet past each other but cannot prevent such return from taking place.

Moreover, if the machine should be started up prematurely, before the rack has become disengaged from the disk, the teeth will merely slide past each other and no harm will be done, nor will any delay in the sewing be occasioned by this occurrence.

In Figs. 4 and 5 there is shown another form of the invention. There the clutch means comprises a pair of disks adapted to engage each other for unidirectional driving. As shown, the main shaft 17a of a sewing machine, carrying a handwheel 18a and a drive pulley 19a, has fastened at its end a clutch disk 22a having around its periphery and extending laterally or axially thereof buttress teeth 23a. A driving disk 24a is carried on a spindle 44 axially aligned with the shaft 17a and journaled in a bracket 45 fastened to the post 13a of the machine, the disk 24a having buttress teeth 27a for engaging the teeth 23a of the disk 22a to drive the latter and the shaft 17a forwardly. The spindle 44 is movable axially as well as rotatable in its journal in the bracket 45, and therefore, the driving disk 24a may be moved axially to engage or disengage the driven disk 22a.

In order to control the axial movement of the driving disk 24a the bracket 45 is provided with a circular cam 46, Figs. 4 and 6, having a pair of quadrant-shaped faces 47 and 48 located on opposite sides of the spindle 44, the portion 49 between the faces being recessed, and the radial edges of the faces being sloped as at 50 (see Fig. 4). Cooperating with the cam 46 is a disk 51, Figs. 4 and 7, fastened on the spindle 44 and having a pair of lugs 52 with sloped radial edges, the lugs being thus adapted, when the spindle 44 is turned, to ride up out of the recessed portions 49 of the cam onto the faces 47 and 48 thereof, and in so doing to disengage the disks 24a and 22a. A helical compression spring 53, carried in a circular groove in the inner face of the bracket 45 to bear against the driving disk 24a, provides a constant pressure tending to move the disk 24a into engagement with the disk 22a for driving. As thus arranged, referring to Fig. 4, the disk 24a is normally disengaged from the disk 22a during operation of the machine for sewing, but if the spindle 44 is turned slightly in a clockwise direction as indicated by the arrow in Fig. 5 to move the lugs 52 past the cam faces 47 and 48, the spring 53 will move the assembled driving disk 24a, spindle

44 and disk 51 axially as permitted by the lugs 52 entering the recesses between the cam faces 47 and 48 and the driving disk 24a will engage the disk 22a. Further clockwise turning of the spindle 5 44 will cause the disk 24a to drive the disk 22a and shaft 17a forwardly, so that the needle of the machine may be positioned where desired.

For the purpose of operating the assembly of driving disk 24a, spindle 44 and disk 51 to position the needle, the disk 24a is provided with a radially extending arm 54, see Fig. 5, which is apertured at its end to pivotally connect with a link 34a extending downwardly through an apertured lateral extension 45a of the bracket 45 to a point under the machine table. The link 34a may be actuated by an operator's lower extremity in the manner shown in Figs. 1 and 2, or by any other suitable foot or leg operated member.

In order to yieldably hold the disks 22a and 24a in disengaged position, a compression spring 42a is carried by the link 34a, one end pressing against the extension 45a of the bracket, and the other end pressing against a collar 43a fixed on the link by means of a set screw. A collar 55 20 is fastened on the link 34a to engage the underside of the bracket extension 45a and act as a stop, the collar positioning the spindle 44 and disk 51 in the rotative position of Fig. 4 wherein the toothed disks are disengaged. The spring 30 42a also serves to return the various parts to their initial positions after the mechanism has been operated to adjust the needle.

As in the form of the invention shown in Figs. 1 through 3, if the machine is prematurely started while the disks 24a and 22a are still engaged, no damage will occur, but the teeth of the disks will merely slide past each other as in a ratchet due to the yielding pressure of the spring 53 and there will thus be no delay in the sewing operations. Normally, the disks 24a and 22a function as a clutch which is disengaged during sewing operation of the machine.

The term "tardigradely" is used herein to mean moving or stepping slowly, or slow pacing.

45 Variations and modifications may be made within the scope of this invention and portions of the improvements may be used without others.

I claim:

1. A needle advancing and retracting device 50 for a sewing machine having a clutch adapted to be connected with the needle-driving mechanism of the machine to adjustably operate same, said clutch having means yieldably holding it in disengaged position; a member mounted for engagement by the lower limb of the operator and movable in response to pressure thereon by the operator; and means connecting said member to said clutch for causing engagement of, and for driving the clutch in response to movement of the operable member whereby the needle driving mechanism of the machine is adjustably operated to advance or retract the needle, the reverse movement of the operable member causing the clutch to disengage in response to said 60 yieldable means and free the needle-driving mechanism for sewing.

2. The invention as defined in claim 1, in which the clutch is adapted for driving in one direction only whereby the needle-drive mechanism of the machine is adjustably operated only by unidirectional movement of the operable member, and whereby said mechanism may be operated for sewing in its forward direction without first disengaging the clutch.

75 3. The invention as defined in claim 1 in which

the clutch comprises a driving member and a driven member, each having co-functioning buttress teeth gripping only for uni-directional relative movement whereby the needle-drive mechanism of the machine is adjustably operated only by uni-directional movement of the operable member, and whereby said mechanism may be operated for sewing in its forward direction without first disengaging the clutch.

4. The invention as defined in claim 1 in which the clutch comprises a wheel fastened to the needle driving mechanism and having buttress teeth around its periphery, and a movably mounted rack having buttress teeth adapted to engage the teeth of the wheel for uni-directional driving thereof whereby the needle-driving mechanism is adjustably operated only by uni-directional movement of the operable member, and whereby said mechanism may be operated for sewing in its forward direction without first disengaging the rack from the wheel.

5. The invention as defined in claim 1 in which the clutch for operating the needle-driving mechanism comprises a pair of wheels having a common axis, each wheel having buttress teeth adapted to engage the teeth of the other for uni-directional relative driving, and one of said wheels being axially movable for engaging and disengaging the other in response to movement of the operable member whereby the needle-driving mechanism is adjustably operated by uni-directional movement of the operable member, and whereby said mechanism may be operated for sewing in its forward direction without first disengaging the said wheels.

6. The invention as defined in claim 1 in which the clutch for operating the needle-driving mechanism comprises a driving and a driven wheel, each having a common axis and having buttress teeth adapted to engage the teeth of the other for uni-directional relative driving, and one of said wheels being axially movable for engaging and disengaging the other, in which there is a cam for controlling the engagement of the axially movable wheel, and in which the operable member is connected to operate said cam and the driving wheel whereby the needle-driving mechanism is adjustably operated by uni-directional movement of said operable member, and whereby said mechanism may be operated for sewing in its forward direction without first disengaging the said wheels.

7. The invention as defined in claim 1 in which the clutch for operating the needle-driving mechanism comprises a driving and a driven wheel, each having a common axis and having buttress teeth adapted to engage the teeth of the other for uni-directional relative driving, and one of said wheels being axially movable for engaging and disengaging the other, in which there are yieldable means for moving the axially movable wheel to engage the other, and in which the operable member is connected to control said yieldable means and to operate the driving wheel whereby the needle-driving mechanism is adjustably operated by uni-directional movement of said operable member, and whereby said mechanism may be operated for sewing in its forward direction without first reversibly moving the said operable member to disengage the said wheels.

8. In a sewing machine a needle advancing and retracting device, including a clutch having a driven disk connected to turn with the main shaft of the machine and a driving disk mounted in axial alignment with the driven disk, each

of said disks having buttress teeth adapted to engage the teeth of the other for uni-directional relative driving, and the driving disk being axially movable to engage and disengage the driven disk; means for yieldably holding the driving disk in engagement with the driven disk; a cam and follower connected with the driving disk for axially moving and holding same out of engagement with the driven disk; an operable member shaped for engagement with an operator's lower extremity; means for movably mounting the operable member on the machine frame; and means for connecting the operable member with the driving disk and cam whereby uni-directional movement of said member will operate the cam to release the disk to engaging position, and will turn the disk to operate the shaft of the machine and advance or retract the needle.

20 9. In a sewing machine, a needle advancing and retracting device having a clutch disk connected to turn with the main shaft of the machine, said disk having buttress teeth around its periphery; a rack having buttress teeth adapted to engage the teeth of the disk for uni-directional driving of the latter to turn the machine shaft forwardly; means for mounting the rack on the machine frame for lateral movement to and from an engaging position with the disk, and for advancing longitudinal movement when engaged with the disk in a direction to drive the latter; means for yieldably holding the rack in retracted position and out of engagement with the disk; an operable member shaped for engagement by an operator's lower extremity; means for mounting the operable member on the machine for movement in response to pressure from the operator; and means responsive to movement of the operable member for operating the rack whereby the latter is caused to engage and to drive the clutch disk to operate the machine shaft for advancing or retracting the needle, and whereby upon release of the operable member same will have its movement reversed and the rack will be disengaged from the disk by said yieldable means.

10 10. In a sewing machine having a main shaft, a needle advancing and retracting device having a clutch disk fixedly carried by the main shaft of the machine to rotatably move same forwardly for positioning the needle, said disk having buttress teeth around its periphery which are positioned so that during forward rotation of the shaft the sloping faces of the teeth lead the driving faces thereof; a driver having a plurality of buttress teeth adapted to engage the teeth of the disk for driving same and the machine shaft forwardly; means for movably mounting the driver on the machine for both rotational and translational movement whereby the teeth thereof may engage and disengage the teeth of the disk and whereby said driver may be moved, while its teeth are in engagement, in a manner to drive the disk; means, including a spiral spring, for yieldably maintaining the driver in a retracted non-driving position where the teeth thereof are disengaged from those of the disk; an operable member shaped for engagement with an operator's lower extremity; means for mounting the operable member on the machine frame for reversible movements; and means responsive to movement of the operable member in one direction by the machine operator for operating the driver against the opposition of the spiral spring whereby the teeth of the disk are engaged

by those of the driver, and the latter is moved to drive the disk and main shaft for positioning the needle of the machine, and whereby, upon release of the operable member, the driver and said member will be returned to their initial positions by the means for yieldably maintaining the driver in retracted position.

11. The invention as defined in claim 8 in which the cam and follower comprise a pair of quadrant-shaped surfaces connected to the machine frame and located on opposite sides of the axis of the driving disk and a pair of lugs attached to the driving disk for engaging said surfaces, said lugs and surfaces having camming edges adapted to engage each other whereby movement of the lugs with respect to the quadrant surfaces controls the axial movement of the driving disk.

12. In a sewing machine, a needle advancing and retracting device having a clutch disk connected to turn with the main shaft of the machine, said disk having buttress teeth around its periphery; a rack having buttress teeth adapted to engage the teeth of the disk for uni-directional driving of the latter to turn the machine shaft forwardly; means for mounting the rack on the machine frame for lateral movement to and from an engaging position with the disk, and for advancing longitudinal movement when engaged with the disk in a direction to drive the latter including a slide fastened to said frame and a pivot carrying said rack and movable in said slide; means for yieldably holding the rack in retracted position and out of engagement with the disk including a spiral spring pressing against the pivot, and another spiral spring providing pressure on the rack at a point removed from said pivot; an operable member shaped for engagement by an operator's lower extremity; means for mounting the operable member on the machine for movement in response to pressure from the operator; and means responsive to movement of the operable member for operating the rack whereby the latter is caused to engage and to drive the clutch disk to operate the machine shaft for advancing or retracting the needle, and whereby upon release of the operable member same will have its movement reversed and the rack will be disengaged from the disk by said yieldable means.

13. In a sewing machine including a frame, stitching mechanism including a needle bar mounted at one end of the frame; a shaft for operating said needle bar; a driving mechanism for said shaft located adjacent the other end of the frame and employed when operating the machine for sewing; and auxiliary means separate from the driving mechanism and located at the end of the frame remote from said needle bar and having a drive member operated by a lower limb of the operator while the hands of the latter are free to engage the work, for inching the

stitching mechanism to move the needle to a desired position relative to the work, said auxiliary means also having spring means for normally urging the drive member into inoperative position.

14. In a sewing machine having a work supporting table, stitching mechanism including a needle bar; a driving mechanism including a drive shaft for the needle bar employed when operating the machine for sewing; and auxiliary means separate from the driving mechanism for rotating said shaft including shaft-actuating ratchet means carried by the shaft, an actuator therefor disposed below the table, a driving connector extending from the actuator to the means on the shaft, and resilient means for normally urging the ratchet means to inoperative position, said actuator being operated by a lower limb of the operator while the hands of the latter are free to engage the work for rotating the shaft and inching the stitching mechanism to move the needle to a desired position relative to the work.

15. In a sewing machine having a work supporting table, a frame; stitching mechanism including a needle bar mounted on one end of the frame; a shaft for operating the stitching mechanism; a driving mechanism for the shaft mounted adjacent the other end of the frame and employed when operating the machine for sewing; and auxiliary means at the latter end of the frame and separate from the driving mechanism for rotating said shaft including means carried by the shaft, an actuator therefor disposed below the table, a driving connector extending from the actuator to the means on the shaft, and resilient means normally urging the driving connection into inoperative position, said actuator being operated by a lower limb of the operator while the hands of the latter are free to engage the work for rotating the shaft and inching the stitching mechanism to move the needle to a desired position relative to the work.
